No. 829,167.

PATENTED AUG. 21, 1906.

A. MILLER.
REFRIGERATOR.
APPLICATION FILED SEPT. 21, 1905.

UNITED STATES PATENT OFFICE.

ADOLPH MILLER, OF ST. LOUIS, MISSOURI, ASSIGNOR TO MILLER MANUFACTURING COMPANY, OF ST. LOUIS, MISSOURI, A CORPORATION.

REFRIGERATOR.

No. 829,167.

Specification of Letters Patent.

Patented Aug. 21, 1906.

Application filed September 21, 1905. Serial No. 279,380.

To all whom it may concern:

Be it known that I, ADOLPH MILLER, a citizen of the United States, residing in the city of St. Louis, in the State of Missouri, have invented certain new and useful Improvements in Refrigerators, of which the following is a full, clear, and exact description, reference being had to the accompanying drawings, forming part of this specification.

10 My invention relates to means for uniting the sections of "knockdown" or sectional refrigerators, whereby said sections may be conveniently, quickly, and efficiently joined and set up.

15 My invention consists in features of novelty hereinafter fully described, and pointed out in the claims.

Figure I is an exterior elevation of part of a refrigerator-wall having the sections thereof 20 united by my connecting construction with one of the fastening-bolt inclosing doors omitted. Fig. II is a vertical section taken through a refrigerator-wall as on line II II, Fig. I. Fig. III is an elevation of my fastening construction. Fig. IV is a horizontal section taken on line IV IV, Fig. III.

The walls of my refrigerator are composed of sections designed to be united in the construction of refrigerators of varying sizes and 30 inclosed within an exterior sheathing. The wall-sections are composed of an inner wall 1, an outer wall 2, and vertical studding 3. The studding 3 are positioned at each end of each wall-section and have their adjacent 35 side faces contacting with each other.

5 is a sheathing secured to the outer face of the outer wall 2 to constitute a facing for the wall-sections. In the studding 3 are horizontal bolt-holes which receive fastening- 40 bolts 6, by which the said studding are connected to join the wall-sections. There may be any desirable number of these fastening-bolts located at intervals in the end studding from top to bottom thereof, so as to securely hold 45 the wall-sections together. The inner walls 1 of the wall-sections are continued throughout directly to the end studding 3 and are therefore in full at the locations of the fasten-

ing-bolts 6. At the locations of said fastening-bolts in the outer wall 2 and sheathing 50 5 are doorways 7, through which access to the bolt-holes through the studding 3 for the introduction of the fastening-bolts see 11. These doorways are closed by doors 8, fitted thereto after the wall-sections have been 55 united by the fastening-bolts.

9 represents three-sided frames consisting of a vertical member and two arms that are secured to the free side faces of the studding 3 at the location of the fastening-bolts, as 60 seen most clearly in Fig. III. These frames serve as members to which the outer wall 2 of the refrigerator-sections may be secured at the locations of the doorways 7 and fastening bolts, and they furnish inclosures through 65 which access may be gained to the bolt-holes in the studding for the introduction of the fastening-bolts in setting up the wall-sections. They also serve as a backing for the doors 8 when they are inserted into the 70 doorways 7 to inclose the fastening-bolts. It will be seen that in setting up a sectional refrigerator having my improvement incorporated therein the sections may be readily and quickly assembled and united by passing 75 the fastening-bolts 6 through the wall-section studding and securing them therein while the doors 8 are absent from the doorways 7. After the fastening-bolts are introduced the doors 8 are put in place, and the refrigerator- 80 wall is completed as fully as it would be in the absence of the doorways through which access to the fastening-bolts is obtained.

I claim as my invention—

1. In a refrigerator, the combination of 85 wall-sections having end studding, bolts connecting said studding and holding their adjacent side faces in contact to unite said sections, doorways affording access to said bolts, and frames applied to the free side 90 faces of said studding at the location of said bolts and inclosing the projecting ends of said bolts to render them accessible in joining the sections, substantially as set forth.

2. In a refrigerator, the combination of 95 wall-sections having end studding, bolts con-

necting said studding and holding their adjacent side faces in contact to unite said sections, doorways affording access to said bolts, three-sided frames applied to the free side faces of said studding at the location of said bolts and inclosing the projecting ends of said bolts to render them accessible in joining the

sections, and doors to close said doorways after said bolts are introduced, substantially as set forth.

ADOLPH MILLER

In presence of—

BLANCHE HOGAN,
E. S. KNIGHT.
